[57] **CLAIM**

The ornamental design for a combined mobile storage cart and rack, as shown and described.

DESCRIPTION

FIG. 1 is a perspective view of a combined mobile storage cart and rack, showing my new design;

FIG. 2 is an elevational view with the two halves shown in open position and with the ball storage well removed;

FIG. 3 is an elevational view of one side, the opposite side being substantially a mirror image thereof;

FIG. 4 is a rear elevational view;

FIG. 5 is a front elevational view;

FIG. 6 is a top plan view; and,

FIG. 7 is a bottom plan view.
